US00D574432S

(12) **United States Design Patent**
Kouda

(10) **Patent No.:** **US D574,432 S**
(45) **Date of Patent:** **** Aug. 5, 2008**

(54) **COATING FILM TRANSFER APPARATUS**

(75) Inventor: **Yoshinori Kouda**, Tokyo (JP)

(73) Assignee: **Tombow Pencil Co., Ltd.**, Tokyo (JP)

(**) Term: **14 Years**

(21) Appl. No.: **29/292,502**

(22) Filed: **Oct. 12, 2007**

(30) **Foreign Application Priority Data**

Apr. 19, 2007 (JP) 2007-010475

(51) **LOC (8) Cl.** **19-02**

(52) **U.S. Cl.** **D19/69**

(58) **Field of Classification Search** D19/66, D19/67, 68, 69, 70; 156/523, 257, 540, 577; 206/411; 225/6, 25, 39, 77; 242/588, 588.1, 242/588.2, 588.3, 588.6, 5

(57) **CLAIM**

The ornamental design for a coating film transfer apparatus, as is shown and described.

DESCRIPTION

FIG. 1 is a front view of the coating film transfer apparatus of the subject invention;

FIG. 2 is a rear view of the coating film transfer apparatus of the subject invention;

FIG. 3 is a top view of the coating film transfer apparatus of the subject invention;

FIG. 4 is a bottom view of the coating film transfer apparatus of the subject invention;

FIG. 5 is a left side view of the coating film transfer apparatus of the subject invention;

FIG. 6 is a right side view of the coating film transfer apparatus of the subject invention; and,

FIG. 7 is a perspective view of the coating film transfer apparatus of the subject invention.
